UNITED STATES PATENT OFFICE.

CLARENCE ROST, OF CANTON, MISSOURI, ASSIGNOR OF TWO-THIRDS TO
M. M. HEAD AND W. M. MORRIS, OF SAME PLACE.

STENCIL.

SPECIFICATION forming part of Letters Patent No. 625,700, dated May 23, 1899.

Application filed January 21, 1898, Serial No. 667,514. (No model.)

To all whom it may concern:

Be it known that I, CLARENCE ROST, a citizen of the United States, residing at Canton, in the county of Lewis and State of Missouri, have invented a new and useful Stencil, of which the following is a specification.

This invention has relation to stencils for lettering, fresco, and ornamental work, and has for its object to enable the letters or design to be stenciled complete without requiring the filling in of spaces caused by strips connecting isolated parts of the stencil with the main portion thereof.

The invention belongs more particularly to the means for supporting the isolated parts of the stencil and holding them in proper position; also, to the provision for stiffening and staying the reentrant parts, having connection with the main portions of the stencil by means of narrow strips, whereby it is possible to use exceedingly thin sheet material in the construction of the stencil, thereby enabling a high grade of work to be accomplished.

For a full understanding of the merits and advantages of the invention reference is to be had to the accompanying drawings and the following description.

The improvement is susceptible of various changes in the form, proportion, and the minor details of construction without departing from the principle or sacrificing any of the advantages thereof, and to a full disclosure of the invention an adaptation thereof is shown in the accompanying drawings, in which—

Figure 1 is a perspective view of a stencil constructed in accordance with this invention. Fig. 2 is a plan view thereof. Fig. 3 is a transverse section on the line X-X of Fig. 2. Fig. 4 is a detail longitudinal section on the line Y-Y of Fig. 2.

Corresponding and like parts are referred to in the following description and indicated in the views of the drawings by the same reference characters.

The stencil comprises a light frame 1 of suitable size and outline, according to the character of the work to be stenciled. This frame, which may be of wood or metal, serves as a support for the stencil and the adjunc-

tive parts and as a guard to prevent the brush from coming in contact with the surface being lettered or ornamented, thereby enabling the work to be quickly performed without requiring any especial care on the part of the operator to prevent daubing or smearing of the work. The stencil 2 is secured to one side of the frame, and its character will depend upon the style of work in hand. The center or isolated parts have connection with cross-bars 3, secured to the opposite side of the frame and provided with arms or projecting portions 4, to which the isolated parts 5 of the stencil are secured. The arms or projecting parts 4 may be formed with or applied to the cross-bars 3, and their size will depend upon the dimensions of the parts 5 to be supported thereby. The cross-bars 3, with their arms or projecting parts 4, will be provided and used in connection with such letters and designs as have center or isolated pieces and which pieces are generally connected by narrow strips or bridges with the body of the stencil. It will thus be seen that the letter or design is wholly unobstructed and may be stenciled entire in the space formed between the inner and outer boundary-lines. This feature of the invention is shown applied to the letters "A," "&," and "O."

Letters, designs, characters, and symbols having reentrant portions 6 connected with the body of the stencil by narrow strips have the said reentrant parts stiffened and strengthened by reinforcements 7, which are cemented or otherwise secured to the rear side of the stencil, and these reinforcements 7 may be of any suitable material which is light and stiff and of such a size as not to project to the outer edge of the parts 6, thereby not interfering with the formation of a sharp outline in the work when completed. Other reinforcements 8 are secured to the body of the stencil to stiffen and brace it. Stay-bars 9 connect the opposing sides of the frame 1 and are secured to the rear side of the stencil and serve to brace both the frame and stencil. These brace-bars 9 are located at breaks in the stencil and between letters.

The thinner the material of which the stencil is formed the more pronounced is the outline of the work and the less the liability for

the stenciling material or pigment to run when the stencil is in use.

The advantages of the invention will be readily appreciated when applied to comparatively large stencils, inasmuch as the stencil is stiff and rigid and at the same time light and capable of being easily handled, and it is not necessary to fill in after the letters or designs have been stenciled.

Having thus described the invention, what is claimed, and desired to be secured by Letters Patent, is—

1. In combination, a stencil and reinforcements conforming approximately to the outline of the separated and isolated parts and secured to the rear side of the stencil for stiffening, strengthening and bracing it, substantially as described.
2. In combination, a frame, a stencil secured to one side of the frame, and bars secured to the stencil and to members of the frame for stiffening, strengthening and brac-

ing the stencil and frame, substantially as set forth.

3. A stencil constructed substantially as specified, the same comprising a frame, a stencil secured to one side of the frame, reinforcements applied to the body and to the reentrant parts of the stencil, brace-bars connecting opposing frame-bars and secured to the stencil, and cross-bars connecting opposite frame-bars at a distance from the plane of the stencil and provided with projecting portions or arms supporting center or isolated parts of the stencil, substantially as and for the purpose specified.

In testimony that I claim the foregoing as my own I have hereto affixed my signature in the presence of two witnesses.

CLARENCE ROST.
